UNITED STATES PATENT OFFICE.

ALBERT V. T. DAY, OF NEW ROCHELLE, NEW YORK.

TRAFFIC-CONTROLLING APPARATUS.

1,185,589.

Specification of Letters Patent. Patented May 30, 1916.

Application filed August 4, 1911. Serial No. 642,232.

To all whom it may concern:

Be it known that I, ALBERT V. T. DAY, a citizen of the United States, residing at New Rochelle, in the county of Westchester and State of New York, have invented certain new and useful Improvements in Traffic-Controlling Apparatus, of which the following is a specification, reference being had therein to the accompanying drawings, forming part thereof.

My invention relates to train-controlling and signaling apparatus of the class which controls the movement of railway trains by automatically applying the air brakes, and which exhibits a signal on the train, generally classified as a cab signal.

The objects of my invention are to reliably exhibit to the engine driver or motorman a signal indicating the condition of the track ahead, and to automatically prevent the train from approaching a danger zone at high speed, while permitting the train to approach a danger zone at lower speed.

I will describe one form and arrangement of apparatus embodying my invention, and will then point out the novel feature thereof in a claim.

The accompanying drawing is a view showing one form and arrangement of apparatus embodying my invention.

Referring now to the accompanying drawing, 15 is a wheel of a railway train or vehicle moving from left to right on the rails R of a railway track divided into successive signaling blocks by the usual insulated rail joints at the successive signal posts A, B and C.

The rails of each block are included in a circuit controlling the home signal H at the rear end of the block, and traceable from the track battery 2 through one track rail R, track relay 3, the other rail R, back to the battery. The semaphores H are controlled by their respectively adjacent track relay through well known intermediary means, and each distant-signal semaphore D may be controlled by the condition of the block second in advance, by any standard method. Each home signal H operates a contact 7-8 for a purpose hereinafter set forth.

Located on the vehicle is a shaft 16 which is driven through bevel gears by the axle of the vehicle wheel 15, and which carries a centrifugal speed-controlled device 18 including the usual weights connected in the

usual manner with a collar 17 slidable on the shaft 16, so that the collar is raised by the centrifugal tendency of the weights, a variable elevation depending on the speed of the vehicle.

An air pipe 23 leads from the usual train pipe of the air brake system, through a hand valve 24 to a discharge orifice controlled by a cone seated valve 59 connected with the armature 60 of the magnet 12 so that the valve will be closed while the magnet is energized, but will fall open when the magnet is deenergized, thus permitting the escape of air from the train pipe, and applying the brakes.

The semaphore-controlled contacts 7, 8, when closed, energize the primary circuit of an induction coil 26, as follows: from the train-controlling battery 25, through contacts 7, 8, primary winding of the induction coil, contact spring 27, vibrating armature 28 and connecting wire back to the battery.

The terminals 31 and 32 of the secondary winding of the induction coil are connected with a condenser 64 and spark electrodes 29 and 30, as indicated, and each time the primary circuit is broken by the vibrating armature, the secondary winding builds up a static charge in the condenser and spark electrodes until the dielectric between the electrodes breaks down and this charge is delivered across the gap. When this spark occurs, electrical oscillations are communicated from one spark electrode 30 through a connecting wire 65 to a wave wire or train-controlling conductor W extending through the block in rear, and this wave wire in turn delivers Hertzian waves or dielectric waves in all directions.

A short wave receiving wire or antenna 33 is carried by the train in parallelism with the wave wire and close thereto, and receives therefrom electric oscillations communicated through the intervening dielectric, each time that the wave wire is energized by a discharge at the spark electrodes. The antenna communicates the oscillations through the wire 34 to one electrode of a coherer 35, the other electrode of which is grounded on the vehicle shaft through a wire 36. Each time the disruptive discharge occurs at the sparking electrodes, the electric oscillations in the coherer close the following local circuit on the vehicle: from one pole of the vehicle battery 45 through the wire 34, coherer 35, wire 36, magnet 42, and connecting wire

2

back to the battery. Each time this local circuit is closed, the magnet 42 attracts its armature 39 until it makes contact with the spring 41 and the tapper 37 carried by the armature strikes the coherer to decohere its particles, thus again breaking the circuit of the magnet 42, the armature of which is thereupon kicked back by a spring 38 bearing on the tappet arm, whereby the armature breaks contact with the spring 41 and reestablishes contact with the stop 40, which contact was broken by the attraction of the armature. The armature 39 is now ready to be again attracted in response to the next discharge between the spark electrodes 29 and 30, and thus it is kept vibrating so long as the train is approaching a clear home signal.

The vibration of the armature 39 alternately closes the following circuits local to the vehicle: one circuit leading from the vehicle battery 45 through the wire 66, armature 39, contact stop 40, wire 52, slow acting magnet 44 and conductor 46 back to the battery; and the other circuit from the same battery through the same wire 66 and armature 39, and thence by a different course through the contact spring 41, connecting wire, and slow acting magnet 43 to the conductor 46 and thence back to the battery. The magnets 43 and 44 are rendered slow acting by copper sleeves 57 and 58 surrounding their cores, so that they retain their armatures 56 and 53 during the short cessations of current in the magnets while the armature 39 is vibrating. But when the armature 39 ceases its vibration, one of the slow acting magnets is continuously de-energized and releases its armature, and thus opens the following local circuit, which remains closed so long as the armature 39 is vibrating: from the local vehicle battery 45, through the wire 66, armature 56 of the slow acting magnet 43, contact stop 55, connecting wire, contact stop 54, armature 53 of slow acting magnet 44, conductor 48, and thence in parallel through the signal lamp 47 and valve-controlling magnet 12 to the conductor 46 and thence back to the battery 45. Hence, so long as the train is approaching a clear home signal, the armature 39 will be vibrating, the slow acting magnets 43 and 44 will both be energized so as to close the local circuit leading through the signal lamp and valve-controlling magnet, and this lamp will indicate a clear home signal ahead, and the valve-controlling magnet will keep the brake-applying valve 59

closed; but as soon as the train is present in a block in rear of an occupied block, and exceeding a predetermined low speed, the light of the signal lamp is extinguished to indicate caution, and the brakes are applied by the valve 59. But when the train is slowed down to the predetermined low speed while approaching a home signal in stop position, the collar 17 of the speed-controlled device will be lowered until an insulating disk 51 on its lower edge presses the contact spring 49 against the contact stop 50, thus closing another local circuit for the signal lamp and valve-controlling magnet, which may be traced as follows: from the vehicle battery 45 through the wire 66, armature 39, contact stop 40, conductor 52, contacts 50, 49, wire 67, and thence in parallel through the signal lamp 47 and valve-controlling magnet 12 to the conductor 46 and thence back to the battery. By closure of the foregoing circuit while the train speed is reduced to the predetermined limit, the signal lamp is lighted and the brake valve 59 closed so that the brakes may be released, and the train may proceed without impediment.

Although I have herein shown and described only one form and arrangement of apparatus embodying my invention, it is understood that various modifications may be made therein within the scope of the following claim without departing from the spirit and scope of my invention.

I claim:

In combination, two successive sections of a railway track, a train-controlling conductor extending through the rear of said sections, means for producing high-potential oscillating current, a track circuit for the advance section for controlling the supply of energy from said producing means to said conductor, a railway vehicle, vehicle-controlling means thereon controlled by oscillations received from said conductor while the vehicle is in the rear section to permit unretarded progress of the vehicle, and speed-responsive means on the vehicle for controlling said vehicle-controlling means to permit progress of the vehicle at reduced speed after cessation of energy from said conductor.

In testimony whereof I have affixed my signature in presence of two witnesses.

ALBERT V. T. DAY.
